(57) **CLAIM**

The ornamental design for a gaming device display, as shown and described.

DESCRIPTION

FIG. 1 is substantially a perspective view of a gaming device display.

FIG. 2 is substantially a front elevational view of the gaming device display shown in FIG. 1.

FIG. 3 is substantially a right side view of the gaming device display shown in FIG. 1.

FIG. 4 is substantially a left side elevational view of the gaming device display shown in FIG. 1.

FIG. 5 is substantially a top plan view of the gaming device display shown in FIG. 1.

FIG. 6 is a front elevational view, showing the design in a second environment;

FIG. 7 is a front elevational view, showing the design in a third environment;

FIG. 8 is a front elevational view, showing the design in a fourth environment; and,

FIG. 9 is a front elevational view, showing the design in a fifth environment.

Broken lines illustrate features or environmental components that are not part of the design sought to be patented.
